UNITED STATES PATENT OFFICE.

EDWARD D. DOUGHERTY, OF PHILADELPHIA, PENNSYLVANIA.

CONDUIT OR BRACKET FOR CABLE RAILWAYS.

SPECIFICATION forming part of Letters Patent No. 364,499, dated June 7, 1887.

Application filed September 3, 1886. Serial No. 212,611. (No model.)

To all whom it may concern:

Be it known that I, EDWARD D. DOUGHERTY, of Philadelphia, in the county of Philadelphia and State of Pennsylvania, have invented a certain new and useful Improvement in Conduits or Brackets for Cable Railways; and I do hereby declare the following to be a full, clear, and exact description of the invention, such as will enable others skilled in the art to which it appertains to make and use the same.

This invention relates to an improvement in conduits or brackets for cable railways.

The object of my improvement is to greatly strengthen the bracket that supports the sections of conduit-pipe and holds them in axial line, so that the weight of the tube and superincumbent mass of earth over same, when in position, will be prevented from spreading the bracket, and also give necessary rigidity to resist the destructive influence of frost; further, to provide, intact with the bracket-body, adequate means for relieving the conduit-pipe at these points of surface-water that is flushed in through the slot of the center plate in which the grip-bar slides; in conjunction with and assisting to effect these desirable features to provide integral with the bracket a suitable support for the pulley-wheels, and so permit them to be held in position independent of the sections of the pipe. These novel features of advantage are attained by the construction of the bracket-wall with suitable projecting flanges for carrying the ends of the pipes and holding same in axial alignment, and by the provision of a peculiarly-formed chambered wheel-support made integral with the bracket-flanges just mentioned; also, by integrally forming a cylindrical web-extension of the bottom of the wheel-chamber, so as to jointly act as a stiffening-brace and as a drain-connection to carry off water accumulation from said chamber.

A detailed description of these novel features is hereinafter given in the specification and illustrated in the drawings annexed, making a part of same, in which—

Figure 1 is a longitudinal section. Fig. 2 is a transverse section of the device in position with wheel-pocket in end elevation, taken on the line $x x$, Fig. 1. Fig. 3 is a view in

section taken on the line $y y$, Fig. 1. Fig. 4 is a cross-section of the cylindrical drain-pipe, taken on line $v v$ of Fig. 2.

In metallic conduits as heretofore constructed the pulley-wheels are situated in the lower portion of the interior of the pipe, mounted in side bearings placed in the walls of said pipe or in shallow pockets, making a part of same, so that a considerable depth is necessary in the conduit to accommodate the pulleys, and a proportionate amount of material is required to provide the requisite space vertically considered, and in consequence of this depth the side walls of the conduit must be made of increased thickness to properly resist the collapsing impact of earth-bed vertical and lateral, and also the deranging results of frost action. In my improved conduit bracket-support the web-flange A is stiffened at its outer edge by a cap-flange, E E, that is made continuous, as shown in Fig. 2; also, its T shape in cross section is shown in Fig. 3.

The body A of the bracket is given the form represented in Fig. 2. It is lightened somewhat at the points $a a$ by suitable orifices cut therein. The top portion of the flange E E is made horizontal, and is provided with lugs at each outer end for the retention in place of the string-pieces $h h$ of the track. (See Fig. 2.) At an intermediate point in the width of the web-flange A there is formed a proper-shaped opening in the vertical wall of same, and two flanges, C' C', are extended at a right angle to the vertical wall at this point, so as to form a short open-top tube of a proper circumferential shape to coincide exactly with the conformation of the collar-flanges C C, made on the ends of the conduit-pipes L L. The flanges C' C' are also made of such relative size to the flanges C C as to permit the latter to be adjusted in place thereon and neatly fit them, and when the conduit-pipes and the supporting-brackets are placed in position in the road-bed this method of connection and adjustment will form a continuous conduit-pipe, and hold the adjusted and coupled sections in axial alignment. Immediately below the center of the short chamber formed by the flanges C' C', and integral with same, a sub-chamber, B, (see Figs. 1 and 2,) is formed of such relative size as to

allow the pulley-wheel H to be properly located therein. This wheel is grooved in the usual manner for the retention and support of the cable, and it is made to revolve upon its 5 axis, which is removably adjusted in place in the chamber B by the ends of the shaft P resting in open-top sockets that are cast in projecting bosses made intact with the side wall of the chamber. It will be noticed that the 10 web-flange A is made integral with the wall of chamber B, joining it at a point corresponding to the axial center of said chamber. A vertically-descending neck-pipe, e, of suitable length, is projected centrally downward from 15 the base-wall of the sub-chamber B, and as this is made cylindrical its caliber will form a communicating passage to connect the lowest point in the sub-chamber B with a sewer or other proper water-drain pipe. An inspection 20 of the drawings will show that the disposition of material in the wheel-chamber B produces an inverted hollow hemisphere with four flattened sides. This double-arched cavity affords the best approved economic form of construction 25 to obtain rigidity in the supporting-bracket A and elastic strength to compensate for expansion and contraction of material; also resist vertical as well as lateral pressure or strain on the parts and the disrupting influence 30 of frost. The cylindrical extension below the crown of the spheroidal chamber B is an additional brace to the bracket-flanges A A, and it will be observed that its perforation of the crown or lowest point in said chamber B 35 will effectually drain it of all surface water that may enter from above.

The affixed position of the stationary shaft P, upon which the pulley-wheel H revolves, is such in relation to the lower interior surface 40 of the conduit L L, supported above it, that the major portion of the pulley-body is contained in the chamber B, and consequently the vertical depth of the projecting flanges that carry the conduit-pipe L L can be materially 45 reduced. The sectional area of the short chamber formed by the junction of these flanges C C is also contracted, so as to permit a comparatively small conduit-pipe to be used. This is evident, as the space required in conduits 50 in which wheels are located interior thereto is rendered unnecessary by my improved method of constructing the wheel-chamber B.

It is obvious from this that a remarkable reduction in amount of material required for

construction is obtained and a consequent 55 economy in cost of manufacturing the conduit-pipes effected.

The cylindrical connection for water removal may be attached to a longitudinal underlying drain-pipe, I, (see Fig. 1;) or by suitable pipe-extension the water may be led off to a laterally-located sewer. 60

It is evident that various modifications in the shape of the several parts of my invention may be made without departure from the spirit 65 of same. I therefore desire sufficient latitude allowed in the descriptive matter, and its relation to the drawings, to permit slight variations therefrom to facilitate mechanical execution, or for other necessary causes that may 70 appear.

Having fully described my invention, what I claim as new, and desire to secure by Letters Patent, is—

1. A cable-railway bracket shaped substantially as described, and provided with a slot 75 for the passage of the grip, an opening or passage-way for the cable, and a chamber below the cable passage-way for a pulley for supporting the cable, substantially as set forth. 80

2. The combination, with a bracket for the support of conduit-pipes of cable railways, having two opposite pipe-supporting flanges, and a wheel-chamber made integral with same, of the wheel and its axle, substantially as set 85 forth. 85

3. In a bracket for conduit-pipes of cable railways, having pipe-supporting flanges and a chambered wheel-support made integral with a lateral flange, the combination there- 90 with of a revolving pulley-wheel, its supporting-axle, and a central drain-pipe, substantially as set forth. 95

4. A cable-railway bracket shaped substantially as described, and provided with a slot 95 for the passage of the grip, an opening or passage-way for the cable, a chamber below the cable passage-way for a pulley for supporting the cable, and a drain-pipe communicating with the pulley-chamber, substantially as set 100 forth.

In testimony whereof I have signed this specification in the presence of two subscribing witnesses.

EDWARD D. DOUGHERTY.
